FIG. 15.

UNITED STATES PATENT OFFICE

2,636,319

POLISHING MACHINE

Webster B. Knight, Detroit, Mich.

Application October 20, 1948, Serial No. 55,585

18 Claims. (Cl. 51—76)

1

The present invention relates to polishing machines and more particularly to an improved machine for finishing the heads of screws and other similar workpieces.

It is conventional in the finishing of chrome-plated screws to obtain the desired bright finish on the screws by what is commonly known as bright plating. This bright plating requires a relatively long period of time and the operators must be very highly skilled to insure proper control of the bath and removal of the workpieces at the proper time. The necessity of employing this delicate and expensive bright plating process may be eliminated by buffing the screw heads after plating. When there is to be a buffing operation after the plating, the plating process may be stepped up considerably and the time thereof cut to a third or less of the time required for the delicate bright plating process, and an operator having little or no skill may be used rather than the very highly skilled operators required for the bright plating process. It has, of course, been known for some time that the necessity of bright plating could be eliminated in this manner by employing a buffing operation after the plating, but there has been no satisfactory known means for performing the buffing operation without undesirably high labor expenses.

Accordingly, it is an object of the present invention to provide an improved machine for buffing the heads of screws and similar workpieces, which machine operates automatically and has a very large output.

Another object of the present invention is to provide an improved machine for finishing the heads of screws and similar workpieces which includes a hopper for receiving a relatively large number of the screws and means which automatically moves the screws from the hopper and past the buffing station.

It is also an object of the invention to provide an improved hopper for screws or other similarly headed workpieces and a finger and slide assembly associated with the hopper adapted to remove the workpieces from the hopper and deliver them along the slide assembly in single file.

It is also an object of the invention to provide such a hopper and finger and slide assembly combination, the construction of which is such that the screws or other workpieces are removed from the hopper freely and without becoming jammed between the hopper and finger and slide assembly.

A further object is to provide an improved hopper for screws and similar workpieces, which

2

hopper has an inclined bottom having a circular slot adapted to receive the shank of the screw or other workpieces, and includes baffle means for facilitating the collection of the screws in the slot.

5 A further object of the invention is to provide an improved conveyor and supporting means adapted to transport and support a plurality of screws or similar workpieces arranged in single file and vertically disposed.

10 It is also an object of the present invention to provide such a conveyor and supporting means adapted to automatically pick up such screws or workpieces at one end and automatically discharge them at the other end.

15 Another object of the present invention is to provide an improved polishing machine including improved means mounting the polishing wheels thereof whereby the wheels may be readily adjusted relative to the workpieces and whereby the pressure with which the polishing wheels are held against the workpieces may be varied as desired.

20 Other and in certain cases more detailed objects will become apparent from a consideration of the accompanying drawings, the following specification and the appended claims.

In the drawings:

Figure 1 is a view in perspective of a machine embodying the invention;

Fig. 2 is an enlarged broken view in longitudinal section of the construction illustrated in Fig. 1, taken substantially along the line 2—2 thereof;

Fig. 3 is an enlarged sectional view of the construction illustrated in Fig. 2 taken substantially along the line 3—3 thereof;

Fig. 4 is an enlarged broken sectional view of the construction illustrated in Fig. 2 taken substantially along the line 4—4 thereof;

40 Fig. 5 is a broken elevational view of the construction illustrated in Fig. 2 taken in the direction of the arrow 5;

Fig. 6 is an enlarged broken sectional view of the construction illustrated in Fig. 5 taken substantially along the line 6—6 thereof;

45 Fig. 7 is a broken plan view of the construction illustrated in Fig. 2 taken from the line 7—7 thereof;

Fig. 8 is an enlarged broken elevational view of the construction illustrated in Fig. 7 taken from the line 8—8 thereof;

50 Fig. 9 is a sectional view of the construction illustrated in Fig. 8 taken substantially along the line 9—9 thereof;

Fig. 10 is a broken sectional view of the con-

struction illustrated in Fig. 8 taken substantially along the line 10—10 thereof;

Fig. 11 is an end elevational view of the construction illustrated in Fig. 1 taken from the right-hand end thereof as viewed in Fig. 1 and showing parts broken away;

Fig. 12 is an enlarged broken sectional view of the construction illustrated in Fig. 11 taken along the line 12—12 thereof;

Fig. 13 is an enlarged broken elevational view of the construction illustrated in Fig. 11 taken from the line 13—13 thereof;

Fig. 14 is a sectional view of the construction illustrated in Fig. 13 taken along the line 14—14 thereof; and

Fig. 15 is a partially diagrammatic view of the drive of the machine illustrated in Fig. 1.

Referring to the drawings, the machine generally comprises a supporting frame generally indicated at 20, a hopper 22 mounted at one end of the frame 20 for rotation about an inclined axis and having a circular slot 24 in which the screws are collected during rotation of the hopper, conveyor means generally indicated at 26 for supporting the screws and conveying them along the machine during the finishing or polishing operation pick-up and transfer means for removing the screws from the slot 24 of the hopper and transferring them to the conveyor means 26, buffering wheels 30 adjustably mounted on the frame 20 for engaging the screws during their travel along the conveyor means 26, and means for driving the hopper 22, the conveyor means 26 and the buffering wheels 30.

Considering the above described elements in greater detail, and referring to Figs. 1, 2 and 5, the hopper 22 is frusto-conical in shape and has an axially extending shaft 32 by means of which it is supported in an inclined position in bearings 34 and 36 mounted on the frame 20. The hopper 22 is mounted on the shaft 32 for rotation therewith by means of plates 38 and 40 disposed on opposite sides of the bottom 42 of the hopper, which are driven by the shaft 32 and are secured to the hopper bottom 42 by means of bolts 44. The shaft 32 is driven from a pulley wheel 46 by means of a bevel gear 48 mounted for rotation therewith which engages and drives a second bevel gear 50 fixed on the shaft 32.

The hopper 22 is provided with a false bottom comprising an annular ring 52 secured to the conical wall of the hopper 22 and disposed in a plane at right angles to the shaft 32. A plate 54 is received within the annular ring 52 and cooperates therewith to define the circular slot 24. The plate 54 is mounted on the annular ring 52 by a plurality of channel-shaped brackets 55 secured to the under sides of the ring 52 and plate 54. The shape of the brackets 55 is such that they will not interfere with the shanks of screws in the slot 24. Adjacent the slot 24, the ring 52 and the plate 54 are recessed as indicated at 56 and 58 to provide an annular channel adapted to receive the heads of the screws and materially reduce the likelihood of the screws which have collected in the slot 24 from being removed therefrom by engaging other screws in the hopper 22. To facilitate the collection of the screws in the slot 24 the hopper is also provided with a baffle 60 having a conical inner wall surface, the inner edge of which engages the annular ring 52 adjacent the recess 58, and the outer edge of which engages the conical wall of the hopper 22. This baffle 60 in effect forms a fillet which prevents the collection of screws in the corner defined by the annular

ring 52 and the conical wall of the hopper 22, and defines a surface directing the screws into the slot 24. In the embodiment illustrated the conical inner surface of the baffle 60 has an apex angle of approximately eighty degrees.

The hopper 22 is also provided with spring fingers 61 mounted on the underside of the plate 54 and projecting upwardly into the slots 24 at spaced intervals thereof for insuring that screws collecting in the slots 24 will be carried around the slot during rotation of the hopper 22.

Referring now in particular to Figs. 2, 5 and 6, the pick-up and transfer means generally indicated at 28 comprises a pair of bars 62 which are secured in spaced, parallel relation by a plurality of brackets 64 spaced therealong and welded thereto. These brackets 64 are U-shaped and are so secured to the bars 62 that there is ample clearance between the upper surfaces of the bars and the web portion of the bracket 64 to permit the heads of screws to pass under the web portion of the brackets when the shanks of the screws are received between the bars 62 and the heads slide along the upper surfaces of the bar 62, as illustrated in Fig. 6. The upper ends of the bars 62, as best illustrated in Figs. 5 and 6 are formed to define finger portions 66 which ride in the recesses 56 and 58 of the ring 52 and plate 54 for the purpose of sliding under the heads of screws moving along the slot 24 toward the finger portions 66 and lifting the screws from the slot 24 onto the bars 62 where they are supported by their heads which slide along the upper surface of the bars 62. To prevent wedging of the screws between the false bottom of the hopper and the bars 62, the finger portions 66 are carefully formed so that they define an axial extension of the slot 24. This is accomplished by curving the finger portions 66 about the axis of the hopper 22. The finger portions 66 are so curved for a length sufficient to insure that prior to the passage of the head of each screw from such curved portion, the shank of the screw has been completely withdrawn from the slot 24.

As is clearly illustrated in the drawings, the fingers 66 are disposed to engage the plate 54 and the ring 52 at a point where they move downwardly during rotation of the hopper 22. In the preferred embodiment illustrated the fingers 66 engage the ring and plate at approximately the one o'clock position, or approximately thirty degrees from the uppermost point of the slot 24. It will be appreciated, of course, that in the above described arrangement the hopper 22 is rotated in a clockwise direction as viewed in Fig. 5.

In spaced relation to its upper end the pick-up and transfer assembly 28 is held in proper position by an arm 68, one end of which is welded or otherwise suitably secured to one of the brackets 64 and the other end of which carries a bushing in which the shaft 32 is journaled. The screws slide down the bars 62 under the force of gravity and their movement therealong is facilitated by a vibrator 70 which is secured to the frame 20 and transmits sufficient vibration to the bars 62 to greatly speed up the travel of the screws down the bars.

At the lower end of the bars 62 the screws are transferred to the conveyor mechanism generally indicated at 26. Referring in particular to Figs. 7, 8, 9 and 10, the conveyor mechanism 26 is mounted on a horizontally disposed longitudinally extending plate 72 bolted to the frame 20, and a second horizontally disposed plate 74 mounted on the frame 20 in spaced relation to

the plate 72 for adjustment toward and away from the plate 72. The adjustment of the plate 74 is effected by means of a screw 15 rotatably mounted on the frame 20 and engaging tapped depending projections 77 on the plate 72. This construction permits varying of the tension in the hereinafter described conveyor belts 76 as desired. These conveyor belts 76 comprise two generally parallelly disposed endless belts of conventional trapezoidal cross-section which are trained over a pair of pulleys 78 mounted in spaced relation on a shaft 80 extending transversely of the machine and rotatably supported in bearings 82 carried by the plate 74. These pulley belts 76 extend along the plate 72 and at its remote end are trained over a second pair of pulley wheels 84 mounted in spaced relation on a shaft 86 rotatably supported in bearings 88 mounted on the plate 72. Intermediate the shafts 80 and 86 the upper sections of the belts 76 run through parallel guide blocks 88 best illustrated in Fig. 4. The upper adjacent corners of these guide blocks are recessed as at 90 to receive the bottom and one inclined side of the belts 76 and support the portions of the belts received in the guide blocks in the partially twisted positions illustrated in Fig. 4 in which the free adjacent inclined surfaces of the belts 76 are disposed in parallel relation. The belts 76 are held against climbing out of the recesses 90 in the blocks 88 by cover plates 92 secured to the upper surfaces of the blocks 88. In operation of the machine these adjacent parallel surfaces of the belt 76 firmly grip the shank portion of the screws therebetween and prevent the screws from being thrown from the belts 76 by the action of the finishing or polishing wheel 30 illustrated in broken lines in Fig. 4. The spacing of the guide blocks 88 is substantially less than that between the pulley wheels of each of the pairs of wheels 78 and 84. This causes the belts 76 to converge between the wheels 78 and the guide blocks 88 and to diverge between the guide blocks 88 and the wheels 84. The block elements 88 back up the belts 76 throughout substantially the entire length of the travel of the screws therealong, and are adjustable toward and away from each other to accommodate screw shanks of different sizes between the adjacent surfaces of the belts 76. To permit this adjustment the elements 88 have laterally outwardly extending legs 94 at spaced intervals therealong which are provided with slots 96 for adjustably securing them to supporting blocks 98 mounted on a plate 72.

The screws are transferred to the conveyor belts 76 at the lower ends of the bars 62, shown in detail in Figs. 7, 8, 9 and 10, where the upper courses of the belts 76 converge as they pass from the spaced pulley wheels 78 to the point where they enter the guide elements 88. To insure proper transfer of the screws from the slide bars 62 to the belts 76 the lower ends of the bars 62 are tapered as illustrated in Fig. 10 to a substantially knife edge at their lower end whereby the shank of the screw may be grasped by the belt immediately upon its swinging beyond the end of the bars 62 which it will be appreciated will be prior to the head of the screw passing clear of the lower end of the bars 62 because of the vertical position of the screw in the inclined slide. Also, to prevent undue wear on the belt 76 the outer lower corners of the lower edge of the bars 62 are rounded off adjacent the lower end of the bars 62, as best illustrated in Fig. 9. The bars 62 are supported and accurately positioned at their

lower end by means of a pair of plates 100 individual to and welded to the lower ends of the bars 62. The outer ends of the plates 100 rest upon the upper surfaces of the guide blocks 88 and are screwed or otherwise suitably secured thereto. The adjacent edges of the plates 100 are parallel and spaced apart a distance equal to the spacing between the parallel bars 62. It will be appreciated that the plates 100 also function to facilitate proper transfer of the screws from the slide bars 62 to the belts 76 in that they properly locate the heads of the screws during the transfer. It will be appreciated, of course, that the upper courses of the belts 76 travel from left to right as viewed in Figs. 2, 8 and 10, and that as the belts 76 diverge, the screws will be dropped and may be caught in a suitable portable bin or other container.

It will be noted that at each end of the conveyor belt 76 the pulleys 78 and 84 over which they are trained are mounted on a single shaft. This arrangement insures that the two conveyor belts 76 will travel at the same speed thereby assuring that there will be no twisting of the screws supported between the conveyor belts 76 during their movement therealong. These pulley wheels 78 and 84 and the shafts 80 and 86 upon which they are carried are driven by means which will be hereinafter described.

As may be seen in Fig. 1, the machine includes two pairs of polishing wheels 30 spaced longitudinally of the conveyor means 26. The two pairs of wheels 30 are independently mounted and driven, by duplicate means. Accordingly, a description of the mounting and drive means for one of the pairs of wheels 30 will suffice for the other. The pair of wheels 30 at the right hand end of the machine as viewed in Fig. 1, are mounted on and driven on a shaft 102 extending axially therethrough which is journaled, intermediate the spaced wheels 30 is a pair of spaced bearing blocks 104 mounted at the outer lower end of an adjustable arm 106 pivotally mounted at its other end on a shaft 108 extending longitudinally of the machine and journaled in bearing blocks 110 mounted on the machine frame 20. The arm 106 is formed in two slidably connected parts which may be adjusted relative to each other by a screw 112 for varying the effective length of the arms 106.

The shaft 102 carries a pulley wheel 114 secured thereto intermediate the bearing blocks 104 and is driven through this pulley wheel 114 by means of a belt 116 trained thereover and also trained over a pulley wheel 118 on the shaft 108. The shaft 108 is in turn driven by a motor 120 mounted on the frame 20 at the base of the machine through a belt 122 trained over a pulley wheel 124 mounted on the motor output shaft 120 and a second pulley wheel 126 fixed to the shaft 108.

For controlling the pressure of the polishing wheels 30 on the workpieces carried by the conveyor means 26 the outer end of the arm 106 is connected through a link 128 to an adjustable plate 130 which is slidably mounted in a substantially vertically extending angle iron frame 132 which is welded or otherwise suitably secured at its lower end to the frame 20. As best illustrated in Figs. 13 and 14, the plate 130 is urged downwardly by a pair of elongated springs 134, the upper ends of which are connected to the plate and the lower ends of which are connected to a transversely extending member 136 of the frame 132. The plate 130 is adjusted relative to the frame 132 by means of a vertically extending

screw 138 rotatably mounted in the transversely extending member 136 and a second upper transversely extending frame member 140. The screw 138 carries a pair of wing-nuts 142, each of which is connected by a pair of springs 144 to the plate 130. It will be appreciated that the springs 144 act in opposition to and counterbalance the springs 134.

It will now be appreciated that the above described construction permits the polishing wheels 30 to be adjusted both vertically and transversely relative to the conveyor means 26 and permits a predetermined desired pressure to be exerted upon the workpieces by the polishing wheels 30 through the action of the springs 134.

A suitable hood partially illustrated at 146 may be provided and, if desired, may be connected with an associated exhaust fan and conduit (not shown).

It will now be appreciated that the other pair of polishing wheels 30 are mounted on arm 148 corresponding to the arm 106 and driven through a shaft 150 disposed in axial alignment with the shaft 108 and driven by a motor 152 corresponding to the motor 120.

Considering now the drive means for the conveyor means 26 and the hopper 22 and referring in particular to Figs. 1, 2, 11 and 15, a suitable motor 154 is mounted in the lower portion of the frame 20 and drives a first transversely extending shaft 156 through a pulley belt 158. The shaft 156 is rotatably mounted in bearing blocks supported on the frame 20 and carries a small spur gear 160 which drivingly engages a larger spur gear 162 carried by a second transversely extending shaft 164 also journaled in bearing blocks supported on the frame 20. The shaft 164 in turn drives a third shaft 166, which is rotatably supported on the frame 20 through a belt 168. The shaft 166 also carries a pair of pulley wheels 170 from which the above described shaft 86, at the right hand end of the machine as viewed in Fig. 1, is driven by belts 172 trained over a pair of pulley wheels 174 fixed to the shaft 86 at opposite sides of the pulley wheels 84. The shaft 80 at the left hand end of the conveyor mechanism 26 is driven from the shaft 86 by a pair of belts 176 trained over pairs of pulley wheels 178 and 180 mounted respectively on the shafts 86 and 88 adjacent the outer ends thereof. The use of the belts 176 relieves the conveyor belts 76 of the load of driving the shaft 80 from which the hopper 22 is also driven as hereinafter described.

The hopper 22 is driven from the shaft 80 by a belt 182 which is trained over a pulley wheel 184, fixed to the rear end of the shaft 80, as best illustrated in Fig. 7, and also trained over the above described pulley wheel 46 which drives the hopper shaft 32, and hence the hopper 22 through the bevel gears 48 and 50 as above described.

The electric motors 152, 120 and 154 may be suitably connected to and respectively controlled by conventional push-button type switches 184, 186 and 188 which may be suitably located on the frame 20.

It will now be understood that a limited variation in the screw size may be permitted for a given width of the hopper slot 24 and spacing of the slide bars 62. For screws not within these limits it is, of course, apparent that a different plate 54 and slide bar assembly 62 may be employed to accommodate the desired screw size.

It will now be appreciated that the above described machine provides an improved means permitting screws from a large mass to be auto-

matically polished with a bare minimum of labor expense thereby making possible the use of short, fast plating processes carried on by relatively unskilled operators.

It will also be appreciated that the applicant's machine may be used for polishing the rough screws prior to plating, permitting a better plating of the heads thereof.

While only one embodiment of the invention has been illustrated and described in detail, it will be readily appreciated by those skilled in the art that numerous modifications and changes may be made without departing from the spirit of the present invention.

What is claimed is:

1. A polishing machine for use in finishing the heads of screws and like workpieces, said machine comprising a hopper mounted for rotation about an inclined axis and having an axially upwardly presenting annular slot adapted to collect said screws and of a width adapted to receive the shanks of said screws but not permit passage of the heads thereof so that the screws are supported with their shanks hanging in said slot, a frame, conveyor means mounted on said frame for supporting said screws in position to be polished, motive means for driving said hopper and said conveyor means and operatively connected thereto, pick up and transfer means connecting said hopper and said conveyor means for removing said screws from said slot and transferring them to said conveyor means said pick up and transfer means including a slide defining a slot communicating at its upper end with said annular slot of said hopper, and polishing means mounted on said frame for polishing said screws during their movement on said conveyor means.

2. A polishing machine for use in finishing the heads of screws and like workpieces, said machine comprising a hopper mounted for rotation about an inclined axis and having an axially upwardly presenting annular slot adapted to collect said screws and of a width adapted to receive the shanks of said screws but not permit passage of the heads thereof so that the screws are supported with their shanks hanging in said slot, a frame, conveyor means mounted on said frame for supporting said screws in position to be polished, motive means for driving said hopper and said conveyor means and operatively connected thereto, a slide connecting said hopper and said conveyor means and adapted to deliver said screws to said conveyor means individually in vertically disposed position with head end up, said slide having a pair of fingers adapted to remove said screws from said slot and defining a slot communicating with said annular slot of said hopper, and polishing means mounted on said frame for polishing said screws during their movement along said conveyor means.

3. Means for handling screws and other similarly headed workpieces comprising a frame, a hopper mounted on said frame for rotation about an inclined axis and having a plate extending transversely of said hopper at right angles to said axis and having an axially upwardly presenting annular slot adapted to collect said workpieces and of a width adapted to freely receive the shank of said workpieces but not permit passage of the heads thereof whereby said workpieces are supported with their head ends uppermost, and an inclined slide assembly connected to said frame and defining a slot for supporting said workpieces in said position, said slide assembly having a pair of fingers at its upper end defining the up-

per end portion of said slot of said slide and disposed so that said upper end portion of said slot of said slide communicates with said annular slot, said fingers being adapted to automatically transfer said workpieces from said slot in said plate to said slot in said slide assembly, and said inclined slide assembly being adapted to convey said workpieces from said hopper and feed them along said slot in said slide assembly.

4. Means for handling screws and other similarly headed workpieces comprising a frame, a hopper mounted on said frame for rotation about an inclined axis and having a plate extending transversely of said hopper at right angles to said axis and having an axially upwardly presenting annular slot adapted to collect said workpieces and of a width adapted to freely receive the shank of said workpieces but not permit passage of the heads thereof whereby said workpieces are supported with their head ends uppermost, and an inclined slide assembly connected to said frame and defining a slot for supporting said workpieces in said position, said slide assembly having a pair of fingers at its upper end defining the upper end portion of said slot of said slide and disposed so that said upper end portion of said slot of said slide communicates with said annular slot, said fingers being adapted to automatically transfer said workpieces from said slot in said plate to said slot in said slide assembly, said inclined slide assembly being adapted to convey said workpieces from said hopper and feed them along said slot in said slide assembly, and means connected to said slide assembly for vibrating the latter for facilitating movement of said workpieces therealong.

5. Means for handling screws and other similarly headed workpieces comprising a frame, a hopper mounted on said frame for rotation about an inclined axis and having a plate extending transversely of said hopper at right angles to said axis and having an axially upwardly presenting circular slot adapted to collect said workpieces and of a width adapted to freely receive the shank of said workpieces but not permit passage of the heads thereof whereby said workpieces are supported with their head ends uppermost, and an inclined slide assembly connected to said frame and defining a slot for supporting said workpieces in said position, said slide assembly having a pair of spaced fingers at its upper end adapted to automatically transfer said workpieces from said slot in said plate to said slot in said slide assembly, said fingers overlying said plate at opposite sides of said circular slot and defining an upper end portion of said slot of said slide communicating with said circular slot, said inclined slide assembly being adapted to convey said workpieces from said hopper and feed them along said slot in said slide assembly, said fingers being disposed to remove said workpieces from said slot in said plate at a point at which the adjacent portion of said plate moves downwardly during normal rotation of said hopper.

6. Means for handling screws and other similarly headed workpieces comprising a frame, a hopper mounted on said frame for rotation about an inclined axis and having a plate extending transversely of said hopper at right angles to said axis and having an axially upwardly presenting circular slot adapted to collect said workpieces and of a width adapted to freely receive the shank of said workpieces but not permit passage of the heads thereof whereby said workpieces are supported with their head ends uppermost, and an

inclined slide assembly connected to said frame and defining a slot for supporting said workpieces in said position, said slide assembly having a pair of fingers at its upper end adapted to automatically transfer said workpieces from said slot in said plate to said slot in said slide assembly, said fingers overlying said plate at opposite sides of said circular slot and defining an upper end portion of said slot of said slide communicating with said circular slot, and said inclined slide assembly being adapted to convey said workpieces from said hopper and feed them along said slot in said slide assembly, and said fingers being so constructed and arranged that during the removal of each of said workpieces from said slot in said plate the head end of the workpiece is moved in the surface of a cylinder whose axis coincides with said inclined axis and the radius of which is equal to the radius of said circular slot whereby jamming of said workpiece in said slots is prevented.

7. Means for handling screws and other similarly headed workpieces comprising a hopper mounted for rotation about an inclined axis and having a plate extending transversely of said hopper at right angles to said axis and having an axially upwardly presenting circular slot adapted to collect said workpieces, and a pair of spaced stationary fingers engaging said plate at opposite sides of said circular slot and defining a slot substantially equal in width to said slot in said plate and communicating therewith, said fingers being adapted to remove workpieces from said slot in said plate.

8. Means for handling screws and other similarly headed workpieces comprising a hopper mounted for rotation about an inclined axis and having a plate extending transversely of said hopper at right angles to said axis and having an axially upwardly presenting circular slot adapted to collect said workpieces, a pair of spaced stationary fingers engaging said plate at opposite sides of said circular slot and defining a slot substantially equal in width to said slot in said plate and communicating therewith, said fingers being adapted to remove workpieces from said slot in said plate, and a portion of said fingers adjacent said plate being curved about said axis whereby during movement of a workpiece along said portion of said fingers movement of the head of the workpiece laterally of said circular slot is prevented.

9. Means for handling screws and other similarly headed workpieces comprising a hopper mounted for rotation about an inclined axis and having a plate extending transversely of said hopper at right angles to said axis and having an axially upwardly presenting circular slot adapted to collect said workpieces, and a pair of spaced stationary fingers engaging said plate at opposite sides of said circular slot and on the side of said plate which moves downwardly during normal rotation of said hopper, said fingers defining a slot substantially equal in width to said slot in said plate and communicating therewith.

10. Means for handling screws and other similarly headed workpieces comprising a hopper mounted for rotation about an inclined axis and having a plate extending transversely of said hopper at right angles to said axis and having an axially upwardly presenting circular slot adapted to collect said workpieces, a pair of spaced stationary fingers engaging said plate at opposite sides of said circular slot and defining a slot substantially equal in width to said slot in

said plate and communicating therewith, said fingers being adapted to remove workpieces from said slot in said plate, and a portion of said fingers adjacent said plate being curved about said axis whereby during movement of a workpiece along said portion of said fingers movement of the head of the workpiece laterally of said circular slot is prevented, and said portion being of such length that throughout the withdrawal of the shank of each workpiece from the slot in said plate, the head of the workpiece travels along said portion of the fingers.

11. Means for handling screws and other similarly headed workpieces comprising a frame, a hopper mounted on said frame and having an annular slot adapted to collect said workpieces, a slide connected to said frame and assembly including stationary spaced finger means defining a slot communicating with said annular slot of said hopper and adapted to pick up said workpieces from said slot, conveyor means connected to said slide assembly and adapted to receive said workpieces from said slide and transport them while securely holding them in predetermined position, said conveyor means including a pair of endless belts, and means mounting said belts for movement along a path such that corresponding courses of said belts converge at one end, diverge at the other end and intermediate these converging and diverging portions move in spaced parallel relation with the adjacent surfaces adapted to grip the shank of the workpieces.

12. Means for handling screws and other similarly headed workpieces comprising a frame, a hopper mounted on said frame and having an annular slot adapted to collect said workpieces, a slide assembly connected to said frame and including stationary spaced finger means defining a slot communicating with said annular slot of said hopper and adapted to pick up said workpieces from said slot, conveyor means connected to said slide assembly and adapted to receive said workpieces from said slide and transport them while securely holding them in predetermined position, said conveyor means including a pair of endless belts, and means mounting said belts for movement at the same speed and along a path such that the upper courses of said belts converge at one end, diverge at the other end, and intermediate these converging and diverging portions move in spaced parallel relation with the adjacent surfaces thereof disposed in spaced parallel relation and adapted to grip the shank of the workpieces.

13. Conveyor means for screws and other similarly headed workpieces comprising a pair of endless V-belts, means including two pairs of spaced wheels mounting said belts in generally parallel relation, a pair of parallel guide elements disposed intermediate the ends of corresponding courses of said belts and having recesses extending longitudinally thereof receiving and oppositely twisting said corresponding courses and supporting them in a twisted position in which one lateral surface of each is disposed adjacent and parallel to a similar lateral surface of the other.

14. Conveyor means for screws and other similarly headed workpieces comprising a pair of endless V-belts, means including two pairs of spaced wheels mounting said belts in generally parallel relation, a pair of parallel guide elements disposed intermediate the ends of corresponding courses of said belts and having recesses extending longitudinally thereof receiving and oppo-

sitely twisting said corresponding courses and supporting them in a twisted position in which one lateral surface of each is disposed adjacent and parallel to a similar lateral surface of the other, said wheels and said guide elements being so constructed and arranged that said courses of said belts converge between one of said pairs of wheels and said elements and diverge between said elements and the other pair of wheels.

15. Polishing wheel supporting means comprising an arm adapted at one end to be pivotally mounted on a supporting element and including means for varying the effective length of said arm, a shaft rotatably mounted in the other end of said arm and disposed substantially at right angles thereto, said shaft being adapted to have at least one polishing wheel secured thereto for rotation therewith, a frame, a polishing wheel positioning element mounted in said frame for movement substantially at right angles to said arm in its normal operating range, a link pivotally connected at one end to said other end of said arm and pivotally connected at its other end to said polishing wheel positioning element, resilient means engaging said wheel positioning element and said frame urging said wheel in one direction, a screw mounted on said frame and carrying nut means threaded thereon, and resilient means connecting said nut means and said wheel positioning element and acting in opposition to said first named resilient means.

16. A hopper for screws and other similarly headed workpieces, said hopper having a bottom having a circular slot adapted, upon rotation of said hopper about an inclined axis, to collect said workpieces therein with the shanks thereof received in said slot, said hopper also having spring fingers mounted on the under side of said bottom and projecting upwardly into said slot for engaging the shanks of workpieces collected in said slot to prevent said workpieces from sliding in said slot and remaining in the lower portion of said slot during rotation of said hopper.

17. Means for handling screws and other similarly headed workpieces comprising a frame, a hopper mounted on said frame and having an annular slot adapted to collect said workpieces, a slide assembly including spaced finger means defining a slot therebetween communicating with said annular slot, said finger means being disposed above the adjacent portion of said hopper defining the adjacent portion of said annular slot for engaging the heads of said workpieces and lifting the said workpieces axially upwardly from said annular slot, and conveyor means connected to said slide assembly and adapted to receive said workpieces from said slide and transport them while securely holding them in predetermined position.

18. A hopper for screws and other similarly headed workpieces adapted to be mounted for rotation about an inclined axis, said hopper having a conical outer wall member and a bottom plate extending transversely thereof and having its upper surface disposed in a plane extending at right angles to said axis, said bottom plate having an annular slot coaxial with said axis and adapted, upon rotation of said hopper about said inclined axis, to collect said workpieces therein with the shanks thereof received in said slot, said plate being fixed to said hopper wall member for rotation therewith, said hopper also having a baffle mounted therein and having a conical surface terminating at its inner edge adjacent said

slot and terminating at its outer edge at the outer wall of said hopper.

WEBSTER B. KNIGHT.
